UNITED STATES PATENT OFFICE.

MAX VON RECKLINGHAUSEN, OF NEW YORK, N. Y., ASSIGNOR TO AIR REDUCTION COMPANY, OF NEW YORK, N. Y., A CORPORATION OF NEW YORK.

MEANS FOR SUPPORTING GAS-HOLDING CYLINDERS.

1,345,042.

Specification of Letters Patent. Patented June 29, 1920.

Application filed February 16, 1917. Serial No. 149,153.

To all whom it may concern:

Be it known that I, MAX VON RECKLINGHAUSEN, a German citizen, and a resident of the city of New York, county of New York, State of New York, have invented 5 certain new and useful Improvements in Means for Supporting Gas-Holding Cylinders, of which the following is a specification.

10 It has been found that in filling cylinders or tanks with gases, such as oxygen, a certain amount of water is introduced into such cylinders or tanks and various means have been employed for separating such water 15 from the gas because its presence in the gas, after the same has been sold and distributed, is objectionable to the purchaser.

One way of preventing the introduction of water with the gas, as oxygen, into the 20 cylinders or tanks has been to provide in or in connection with the pipe from which the gas is delivered into the said cylinders or tanks what is known as purging means for eliminating and separating out the water 25 from the gas. However, this practice is found to be unsatisfactory because of the rapid movement of the gas in such pipe and in the so called purging means, the water being carried along with the gas due to its 30 rapid movement. The separation, as obviously would be the case, takes place more effectively and more completely at points where the gas is as nearly quiescent or stationary as may be possible.

35 It is my idea that the water, if any be present, may be more effectively and completely separated from the gas after it has been delivered into the cylinder or tank and to this end it is desirable that the cylinders 40 or tanks be filled upside down. The water being in the form of a liquid seeks the lowest point in the cylinder or tank and when the tank is in inverted position the water will collect at its lower end and may be permitted to escape through the opening in the 45 neck or head of the bottle through which the cylinder or tank has been filled.

These cylinders or tanks are quite heavy 50 and are more or less difficult to handle, consequently I have provided means whereby they may be readily placed in position by the workmen and held in inverted position with the openings or opening in the neck or head thereof in proper relation to the end of

a filling tube having connection with the 55 distributing pipe for distributing the gas.

In the accompanying drawings I have 60 illustrated one constructional form of a supporting device embodying my invention and have indicated the manner in which I propose to use the same. It should be understood, however, that various changes in the 65 details of construction may be made without departing from the scope of my invention as the same is set forth in the specification and claims which follow.

In the drawings:

Figure 1 is a central longitudinal sectional view of a device embodying my invention, a portion of the stopping means 70 for retaining the said supporting means and the cylinder or tank therein in upright position, the cylinder or tank being in inverted position.

Fig. 2 is a similar view which includes the 75 said stopping means and shows the supporting means and the cylinder or tank in a substantially upright position.

Fig. 3 is a transverse sectional view taken 80 on the line 3—3 of Fig. 1; and

Fig. 4 is a transverse sectional view taken 85 on the line 4—4 of Fig. 1 and looking toward the right in said figure.

Referring to the drawings, 1 and 2 designate the opposite side members of a metallic 90 frame connected at their rear ends by a cross bar 3 integral or otherwise connected therewith. When in horizontal position, as shown in Fig. 1, the rear end of the said frame rests upon an abutment or support 95 4 which rests on the foundation or the floor upon which the device as a whole stands. The forward ends of the sides 1 and 2 are connected to the lower opposing ends 5 of a frame member 6. The ends of the said side 100 members 1 and 2 and the ends 5 of the frame member 6 may be rigidly secured together in any suitable manner. As shown, I have provided the forward ends of the side members 1 and 2 with short upwardly extending projections 7 which are riveted to the adjacent lower end portions of the sides of the frame 6, while the lower ends of the said sides 6 are provided with rearwardly extending projections 8, which also are riveted to the 105 sides 1 and 2 adjacent to their forward ends.

The forward ends of the sides 1 and 2 and the end portions 5 of the frame 6 are

5 pivotally supported upon a pivot rod 10 supported upon upwardly extending portions 11 of a bracket 12 secured by means of bolts 13 or otherwise to the foundation or other support upon which the device rests or stands.

10 15 and 16 designate respectively 2 couples of rollers secured in opposite relation to each other to intermediate portions of the sides 1 and 2, as shown in the drawing. These rollers may be supported in any suitable manner upon the said sides 1 and 2 and are adapted to support the cylinders or tanks 16^a upon the said side pieces 1 and 2, as is very clearly indicated in the drawing.

15 In placing the cylinders or tanks 16^a upon these supports the forward end portions thereof may be placed upon the rollers 15 and thereafter the said cylinders may be slid or rolled forwardly along upon the said rollers into the position shown in Figs. 1 and 2 of the drawings, and when in such position may be movably held by means of a spring 17 which contacts with the upper side of the said cylinder or tank 16^a, the said spring being secured upon the lower side of a cross bar 18, pivotally secured at 19 to the upper end of a standard 20. The opposite end of the said bar 18 is adapted to be detachably connected with the upper end of a standard 21 by means of a binding nut device 22.

20 25 designates rollers mounted upon radially positioned pivot supports 26, the axes of the said pivot supports extending slightly forward, as indicated in the drawings, so as to adapt the peripheries of the said rollers 25 to rest truly, that is to say, substantially at right angles to the surface of the shoulder portion 27 of the cylinder or tank 16^a.

25 40 It is to be understood, however, that my invention is not limited to the particular construction of rollers as shown nor to the particular manner of supporting the same which is shown.

45 45 I have shown three of these rollers 25, but it will be understood that this number may be increased if desired.

50 55 The presence of these rollers 25 facilitates rotation of the cylinders or tanks 16^a for the purpose of permitting them to be readily positioned in order that the valve closed opening at 30 in the neck 31 of the cylinder or tank may be positioned accurately with respect to the end of a pipe 32 having connection with a distributing pipe 33 having connection with a source (not shown) of gas which is to be introduced or delivered into the cylinders or tank 16^a.

60 65 In order to permit the end of the neck of the cylinder or tank to be moved to the position indicated in Fig. 2 of the drawings and also in order to permit persons having charge of the filling of the said cylinders or tanks to have access readily to the necks of the said cylinders or tanks for the purpose

of connecting the tubes 32 thereto a pit is provided, as partially indicated at 34.

70 In order that the cylinders or tanks and the supporting frames therefor may be supported and sustained in upright position, as indicated in Fig. 2 of the drawings, I have provided a bar 35 arranged in substantial parallel relation to the axis of the pivot rod 10 and which is situated in a plane a distance above a horizontal plane through the 75 said pivot. The said bar is situated forwardly of the said pivot as shown and is supported upon supporting standards 36 (only one of which is shown).

80 While I have shown but a single pivoted cylinder or tank supporting frame, it will be understood that these frames may be duplicated and positioned at intervals side by side, and it will also be understood that a single frame may be constructed of a 85 width sufficient to hold a plurality of cylinders or tanks side by side, such frames being provided with a plurality of supporting means, such as is shown upon the frame as illustrated, for holding the respective 90 cylinders or tanks.

I claim:

1. A frame for supporting a member, said frame being provided with rotatable supporting means intermediate its ends for supporting said member, said supporting means being adapted to rotate in planes substantially parallel to the axis of said member and also with supporting means at one end for contacting with different points upon 100 the end portion of said cylinder to support said cylinder when it is in upright or partially upright position.

2. In combination, a frame pivoted adjacent to one of its ends to stationary pivots, 105 said frame adapted to occupy either a substantially horizontal or an upright position and being provided with means for supporting a member, a stop member situated in a plane forwardly of the point of pivotal support of the said frame and also in a horizontal plane a distance above a horizontal plane through the said point of pivotal support, substantially as described.

3. A frame for supporting cylinders for holding a gas, said frame being provided with rotatable supporting means intermediate its ends for supporting a cylinder and also being provided with rotatable supporting means at one end for contacting with 115 the end portion of said cylinder and supporting the same when in upright position.

4. A frame for supporting cylinders for holding a gas, said frame having rollers supported at opposite sides thereof intermediate its ends and upon which a cylinder is adapted to rest and the said frame being provided at its forward end with a frame-like portion having rollers mounted on radial supports, the said rollers being adapted 125 130

to contact with the forward end portion of the said cylinder, substantially as described.

5. A frame adapted for supporting a cylinder for holding a gas, the said frame comprising side bars having intermediate their ends one or more rollers upon which a cylinder is adapted to rest, said rollers lying in planes extending longitudinally of said cylinder, and the said frame also terminating 10 at its forward end in a laterally extending frame-like portion, which portion is provided with rollers which are adapted to contact with the forward end portion of the said cylinder for supporting the same when 15 in inverted upright position, substantially as described.

6. A frame adapted to support a cylinder for holding gases, said frame comprising sides each having one or more rollers secured thereto intermediate its ends for supporting a cylinder, a laterally extended frame-like portion connected to the forward ends of the said sides, a pivot support for the forward end of the said frame 25 and rollers pivoted upon the said laterally extending frame-like portion, the axes of said rollers extending radially with respect to the longitudinal axis of such cylinder as may be placed upon the said frame-like 30 support, substantially as described.

7. A frame structure for supporting a cylinder adapted to hold gases, said frame

structure being provided with revoluble supporting means intermediate its ends for supporting a cylinder, yielding means for 35 securing the said cylinder upon the said frame structure, the said frame structure comprising a portion at its forward end extending laterally thereof, said portion being provided with a plurality of rollers arranged in spaced relation with respect to each other and radially arranged pivot supports for said rollers carried by the said portion, substantially as described.

8. In combination, a frame pivotally supported adjacent to one of its ends, said frame being adapted to occupy either a substantially horizontal or an upright position and being provided with rotatable means intermediate its ends for supporting a cylindrical member and being provided with means for engaging with one end portion of said cylindrical member when the said frame is in upright or partially upright position to support the same, and means for 55 retaining the said member in position upon said frame when the latter is in upright position.

In testimony that I claim the foregoing as my invention, I have hereunto signed my 60 name this sixth day of February A. D. 1917.

MAX VON RECKLINGHAUSEN.
